CLAIM

The ornamental design for a air intake for a vehicle, as shown and described.

DESCRIPTION

This application contains subject matter related to the following co-pending U.S. design patent applications:

Application Ser. No. 29/763,257, filed Dec. 22, 2020 and entitled “Truck Cab, Toy, and/or Replicas Thereof;” and Application Ser. No. 29/763,258, filed Dec. 22, 2020 and entitled “Truck Cab, Toy, and/or Replicas Thereof.”

FIG. 1 is a right, front perspective view of a first embodiment of an air intake for a vehicle according to the design; FIG. 2 is a left, top perspective view thereof;

FIG. 3 is a front view thereof;

FIG. 4 is a left perspective view thereof; and

FIG. 5 is a top view thereof.

FIG. 6 is a left, front perspective view of a second embodiment of the air intake for a vehicle according to the design; FIG. 7 is a right, top perspective view thereof;

FIG. 8 is a front view thereof;

FIG. 9 is a right perspective view thereof; and,

FIG. 10 is a top view thereof.

The broken lines in the drawings illustrate environmental subject matter only and form no part of the claimed design.

1 Claim, 10 Drawing Sheets
